BRACELET AND METHOD OF MAKING SAME

Leslie Kreisler, Teaneck, and John G. Siska, Cresskill, N. J., assignors to Jacques Kreisler Manufacturing Corporation, North Bergen, N. J., a corporation of New Jersey

Application August 23, 1946, Serial No. 692,617

6 Claims. (Cl. 63—4)

1

This invention relates to bracelets or the like, and to a method of making the same.

More particularly, the instant invention relates to bracelets of the general type disclosed in the co-pending application of Leslie Kreisler, Serial No. 673,691, filed May 31, 1946.

It is the primary object of the present invention to provide a bracelet, or the like, which is fabricated from individual spiral links that are joined without any special connecting elements, and which assumes the appearance of obliquely interwoven, continuous bands rather than that of joined spiral links.

It is another important object of the present invention to devise a method of fabricating bracelets of this type which lends itself to highly efficient mass production of the bracelet at extremely low cost.

The above and other objects, features and advantages of the present invention will be fully understood from the following description considered in connection with the accompanying illustrative drawings.

In the drawings:

Fig. 1 is an enlarged elevational view of a section of a bracelet embodying the present invention;

Fig. 2 shows the individual links as they are coordinated prior to their formation into the bracelet shown in Fig. 1;

Fig. 3 is a top plan view of the coordinated links shown in Fig. 2;

Fig. 4 illustrates an intermediate step in the formation of the coordinated links into bracelet form;

Fig. 5 is a fragmentary side elevation of the parts shown in Fig. 4 as viewed in the direction of the arrow 5 in Fig. 4;

Fig. 6 is a top plan view of the bracelet shown in Fig. 1, prior to the removal therefrom of pins used temporarily in the manufacture of the bracelet;

Fig. 7 is a fragmentary section taken on the line 7—7 of Fig. 1;

Fig. 8 is a fragmentary side elevation of the bracelet, drawn to a larger scale than in Fig. 1; and

Fig. 9 is a fragmentary section taken substantially on the line 9—9 of Fig. 8.

Referring to the drawings, the reference numeral 20 designates a bracelet (Fig. 1) which is fabricated from individual links 22 (Figs. 2 and 3). The links 22 are in the form of spirals made preferably from flat, or relatively flat, metal stock. In the present instance, the spiral links 22 are

2

made from half-round stock as shown in cross section in Figs. 7 and 9. The links 22 are of two types, namely, oppositely directed or wound spirals 22a and 22b (Figs. 2 and 3), which are used alternately in the fabrication of the bracelet for a reason which will become clear hereinafter.

In fabricating the bracelet, as many links 22 as are required therefor are initially assembled by intermeshing the convolutions 26 of alternate links 22a and 22b in the fashion shown in Figs. 2 and 3, and extending temporary pins 28 through the openings 30, formed by the intermeshed convolutions of adjacent links 22 (Fig. 3), to hold the parts in the assembled relation shown in Fig. 2. The links 22 and temporary pins 28 assembled in the relation shown in Fig. 2 are hereinafter referred to as the "link assembly" 32. It will be noted in Figs. 2 and 3 that the adjacent ends 24 of consecutive links 22 in the assembly 32 are disposed alternately on opposite sides of the latter, for a purpose which will become evident hereinafter.

The adjacent ends 24 of the links 22 of the assembly 32 may next be placed between platens 34 (Figs. 4 and 5) which are relatively movable to and from each other. On relative movement of these platens 34 toward each other, the interposed ends 24 of the links 22 are bent inwardly toward their adjacent pins 28 to an extent similar to that shown in Fig. 4, for a purpose which will become obvious hereinafter.

The link assembly 32 is next placed between rams 36 shown in dot-and-dash lines in Fig. 2, which preferably have holes 38 for the reception of the adjacent ends of the pins 28 of the link assembly 32. The rams 36 are relatively movable to and from each other. On relative movement of the rams 36 toward each other, the spiral links 22 of the interposed assembly 32 are axially compressed and their intermeshed convolutions 26 forced into permanent engagement with one another (Figs. 1, 7 and 8). In order to prevent expansion of the links 22 laterally of the assembly 32 during their compression between the rams 36, the link assembly 32 is placed between opposite non-yielding retainer platens 40 shown in dot-and-dash lines in Figs. 3 and 6.

In compressing the link assembly 32 between the rams 36 as described, the opposite ends 24 of each link 22 will also be forced or wedged between the adjacent pin 28 and the adjacent end convolutions 26 of the next link 22 in the fashion best shown in Figs. 6 and 7, thus forming approximately straight side edges 42 on the bracelet (Figs.

1 and 8). Hence, the adjacent end convolutions 26' of the links 22 of the compressed assembly 32 are interconnected by the wedged-in ends 24 of said links, as will be readily understood. Of course, the inward bends previously imparted to the ends 24 of the links 22 of the assembly by the platens 34 (Fig. 4), facilitate the intercurling of the end convolutions 26' of said links, in that the inwardly bent ends 24 are in more favorable disposition for their forced entry between the adjacent pins 28 and the nearest end convolutions of the adjacent links 22.

After removing the compressed link assembly 32 from between the rams 36, and the pins 28 from the assembly 32, the bracelet is completed, and it may then undergo a plating process or any other embellishing process.

In compressing the link assembly 32 as described, the same is elongated longitudinally as follows clearly from a comparison between Figs. 1 and 2 and also between Figs. 3 and 6. The link assembly 32 is, during its compression, elongated longitudinally since the links 22 thereof are prevented from expanding transversely of the assembly 32 by the retainer platens 40 (Figs. 3 and 6). By preventing expansion of the links 22 transversely of the assembly 32, the thickness of the bracelet is kept within narrow limits and the same may have a slender appearance, while longitudinal expansion of the link assembly 32 in consequence of its compression enhances its pleasant appearance of obliquely interwoven, continuous bands 50, 52, 54 and 56, for instance (Fig. 1). Compression of the link assembly 32 also effects a positive interlock between the intermeshed convolutions 26 of adjacent links 22. The interlock between the intermeshed convolutions 26 of adjacent links 22 is two-fold. Thus, the intermeshed convolutions 26 are, in consequence of the compression of the links 22 of the assembly 32, deformed at their intersections in a manner approximately like that shown at 58 in Fig. 9. The portions of the intermeshed convolutions thus deformed are firmly interlocked, and the interlock thus obtained between adjacent links 22 is in itself sufficient effectively to resist separation of these links. In addition, the intermeshed convolutions 26 of adjacent links 22 of the assembly 32 are, also in consequence of the compression of the latter, projected into each other as shown at 60 in Fig. 8, to the extent that they resist separation of the links.

The described interlock between the adjacent links of the bracelet, while being a limited interlock in the sense that the adjacent links 22 of the bracelet are permitted to pivot slightly about axes parallel to their longitudinal axes, nevertheless lends such considerable tensile strength to the bracelet that it will not come apart even on the application of force which is considerably greater than that to which the bracelet is subjected in ordinary usage. The adjacent links 22 of the bracelet are even further, and quite considerably, reenforced against separation from each other by the interlinked or intercurled end convolutions 26' of said links (Figs. 6 and 7).

As shown in Fig. 3, the links 22 from which the bracelet is fabricated are oval, or generally oblong, rather than round in shape, securing the advantage that more nearly cylindrical openings 30 of maximum cross-sectional area between the intermeshed convolutions 26 of adjacent links 22 permit the ready assembly of said links 22 with strong temporary pins 28 of relatively large diameter. The generally oblong shape of the

links 22 secured the further, important advantage that the bracelet will be more slender, and will enhance its appearance of obliquely interwoven, continuous bands rather than have the unsightly appearance of connected spiral elements. Hence, despite its very considerable tensile strength, the bracelet may be slender in appearance, particularly since the oblong links 22 may be made of relatively heavy stock without appearing unduly bulky in the bracelet.

The links 22 from which the bracelet is fabricated are extremely simple and inexpensive to make. Furthermore, the described steps of assembling the links 22 and forming them into the bracelet 20 constitute a method which lends itself to highly efficient mass production of the bracelet at very low cost.

While the abovedescribed method of making the bracelet contemplates the use of temporary pins 28, it is to be understood that these pins may be dispensed with altogether. So long as the intermeshed elements 22 (Figs. 2 and 3) are confined between the retainer platens 40, they will remain in their intermeshed relation without the aid of the pins 28, and will be axially compressed by the rams 36 (Fig. 2) into the form of the bracelet shown in Fig. 1. The elements 22 may, of course, be intermeshed as shown in Fig. 2, and placed between the retainer platens 40, without the aid of the temporary pins 28, as will be readily understood.

While we have shown and described several forms of our invention, it will be understood that our invention may be embodied otherwise than as herein illustrated or described and that various changes may be made in the details of construction and in the arrangement of parts without departing from the invention as defined by the patent claims.

Having thus described our invention, what we claim and desire to secure by Letters Patent is:

1. A bracelet band, comprising a series of alternate, oppositely directed spiral elements arranged side by side with the convolutions of adjacent elements in meshed relation, the intermeshed convolutions of adjacent elements being at each of their intersections mutually deformed into mutual interlocked relation to prevent substantial relative movement between said adjacent elements, said interlock between the intermeshed convolutions of adjacent elements solely holding the latter against separation.

2. A flexible bracelet band, comprising an assembly of alternate, oppositely directed spiral elements arranged side-by-side with the convolutions of adjacent elements in meshed relation, the intermeshed convolutions of adjacent elements being at each of their intersections mutually deformed into mutual limited interlocked relation to prevent substantial relative movement between said adjacent elements, other than restricted relative pivotal movement therebetween about axes parallel to their longitudinal axes, said interlock between the intermeshed convolutions of adjacent elements solely holding the latter against separation.

3. A flexible bracelet band as set forth in claim 2, in which each spiral element is formed of substantially flat band stock disposed widthwise substantially parallel to the longitudinal axis of the element.

4. A flexible bracelet band as set forth in claim 2, in which the elements have generally oblong convolutions and are disposed in the band so that

they extend with the longer dimensions of their convolutions longitudinally of the band.

5. A flexible bracelet band as set forth in claim 2, in which each spiral element is formed of substantially flat band stock disposed widthwise substantially parallel to the longitudinal axis of said element, and said elements have generally oblong convolutions and are disposed in the assembly so that they extend with the longer dimensions of their convolutions longitudinally of the assembly.

6. A flexible bracelet band, comprising a series of alternate, oppositely directed spiral elements arranged side by side with the convolutions of adjacent elements in meshed relation, the adjacent end convolutions of adjacent elements being intercurled and the intermeshed convolutions of adjacent elements being at each of their intersections mutually deformed into mutual limited interlocked relation to prevent substantial rela-

tive movement between said adjacent elements, other than restricted relative pivotal movement therebetween about axes parallel to their longitudinal axes, said intercurled end convolutions and said interlock between the intermeshed convolutions of the adjacent elements solely holding the latter against separation.
